INHALER

Byron Ferris, Portland, Oreg., assignor to Inhealer Laboratories Ltd., Portland, Oreg., a corporation of Oregon

Filed June 11, 1962, Ser. No. 70,508

Term of patent 14 years

(Cl. D83—1)

Fig. 1

Fig. 2

Fig. 3

Fig. 4

Fig. 5

FIG. 1 is a front elevation of the inhaler;
FIG. 2 is a side elevation of the left side of the inhaler;
FIG. 3 is a back elevation of the inhaler; and
FIG. 4 is a side elevation of the right side of the inhaler.
FIG. 5 is a fragmentary section taken on line 5—5 of FIG. 1.

The bottom of the inhaler not disclosed is substantially flat and unornamented, with an electric cord fragmentarily shown for convenience of illustration.

I claim:

The ornamental design for an inhaler, as shown and described.
